UNITED STATES PATENT OFFICE

158,625

ELECTRICAL MUSICAL INSTRUMENT

George H. Stephens, Glencoe, Ill., assignor to
Hammond Instrument Company, Chicago, Ill.,
a corporation of Delaware

Application April 7, 1949, Serial No. 1,857

Term of patent 14 years

(Cl. D56—2)

To all whom it may concern:

Be it known that I, George H. Stephens, a citizen of the United States, residing at Glencoe, in the county of Cook and State of Illinois, have invented a new, original, and ornamental Design for Electrical Musical Instruments, of which the following is a specification, reference being had to the accompanying drawing, forming part thereof.

Figure 1 is a perspective view of an electrical musical instrument, showing my design; and

Figure 2 is a side elevational view thereof, to a reduced scale.

I claim:

The ornamental design for an electrical musical instrument, as shown.

GEORGE H. STEPHENS.
